UNITED STATES PATENT OFFICE.

CLARENCE A. STRACHOTA, OF ST. PAUL, MINNESOTA.

FURNACE ARCH FOR BOILERS.

Application filed May 12, 1922. Serial No. 560,337.

To all whom it may concern:

Be it known that I, CLARENCE A. STRACHOTA, a citizen of the United States, residing at St. Paul, in the county of Ramsey and State of Minnesota, have invented certain new and useful Improvements in Furnace Arches for Boilers; and I do hereby declare the following to be a full, clear, and exact description of the invention, such as will 5 enable others skilled in the art to which it appertains to make and use the same.

My present invention relates to furnace arches such as used in connection with boilers in steam-generating plants and in steel 15 plants, in glass factories and various other places, and is particularly directed to the improvement of what is known as "single fire arches" or arches wherein there is but one block hung in a vertical direction from 20 the metallic overhead support. Generally stated, the invention consists of the novel devices and combinations of devices herein-after described and defined in the claims.

The invention is directed chiefly to simplified and improved means for detachably hanging the blocks from the supporting beams in such a manner that any defaced arch block may be dropped out of position and a new block substituted therefor without disturbing the other blocks of the arch. 25 However, the invention involves certain other novel features, as will hereinafter appear.

In the accompanying drawings, which illustrate the invention, like characters indicate like parts throughout the several views.

Referring to the drawings:

Fig. 1 is a vertical section showing an 35 arch embodying my invention and associating with an apron wall, some parts being broken away;

Fig. 2 is a transverse vertical section taken on the line 2—2 of Fig. 1;

Fig. 3 is a perspective showing one of the 40 radial or wedge-shaped blocks of the arch;

Fig. 4 is a detail in perspective showing one of the block hangers;

Fig. 5 is a perspective showing a shelf-forming plate and its hanger bracket or head removed from working position;

Fig. 6 is a perspective showing the shelf-forming plate of Fig. 5 removed from its hanger bracket;

Fig. 7 is a view corresponding to Fig. 2,

but illustrating a modified form of the block hanger;

Fig. 8 is a perspective showing one of the main arch-forming blocks of the type used in Figs 1, 2 and 7;

Fig. 9 is a perspective showing one of the block hangers of the structure illustrated in Fig. 7; and

Fig. 10 is an elevation showing a modified form of beam hanger.

The fire arch is supported from transverse main beams 10 and 11, which beams are preferably I-beams, the ends of which will be anchored in the side walls of the furnace. In practice, there will be another I-beam 10, 70 at the left in respect to Fig. 1, to support that portion of the arch that is broken away in said view. Slidably hung on the lower flanges of the beams 10 and 11 are beam hangers 12 having inturned laterally spaced 75 fulcrum lugs 13. The beam hangers 12 are aligned on the main supporting beams, so that their lugs 13 will engage short upper flanges 14^a and 14, respectively, on laterally spaced secondary arch-supporting beams 15 80 and detachable beam tips 16. The above described arrangements of beams and beam tips are found in the commercial furnace arch known as the "Liptak" arch and are not herein broadly claimed. The supplemental beams 15, at their lower edges, have longitudinally extended flanges 17, while the beam tips or detachable sections 16 are provided with similar lower edge flanges 18 85 that are curved upwardly at 18^a through 90 approximately ninety degrees.

Mounted to slide on the beam flanges 17, 18—18^a are metallic block hangers, the preferred form of which is illustrated in Figs. 1, 2 and 4. These block hangers, as there 95 shown, are in the form of flat elongated metal loops 19 slotted at 20 and having outwardly projecting lips 21. These hangers are adapted to freely slide on the above noted beam flanges 17, 18—18^a.

The main body of the arch is made up of highly refractory blocks 22 and the upwardly curved or radial end portion of the arch is made up of blocks 23 of similar construction, except that they are made wedge-shaped to form the segments of a circle or similar curve. In their upper ends, the blocks 22 and 23 are formed with seats that adapt them to be interlocked to and hung upon the co-operating block hangers 19. As 100 105 110

preferably designed and as illustrated, said blocks 22 and 23, in their tops, are formed with channels 24, the sides of which are undercut at 25 to form seats to receive the 5 projecting lips 21 of the block hangers. The ledges 26 that overhang the seats 25, at one side of the block, are cut away or cut back at 27 to afford vertical clearance for the lips 21. This general arrangement is important 10 because it not only permits any one of the blocks 22-23 to be removed without disturbing the adjacent block, but it permits this to be done without moving the block hanger 19 of the removed block into an adjacent block. When a block is to be placed in position, it is forced upward to the proper place and then the metallic hanger 19 is slid under the ledges 26 and into the seats 25, in which positions they will support the blocks 15 20 from the beams. When a block is to be removed, it is only necessary to slide the block hanger 19 thereof into the clearance spaces 27 of that block, and thereupon, the said block may be dropped out of the arch. It 25 will thus be seen that each block and its hanger operates as an independent unit, adapting any block or any desired number of blocks, which may have been burned away or damaged, to be dropped from the arch 30 and permitting another block or blocks to be substituted therefor, without disturbing those blocks that do not require replacement.

The numeral 28 indicates a heavy beam, as shown an I-beam, that extends above the 35 beam 11 and may be supported at its ends from the side wall of the arch. Mounted to slide on the lower flanges of the beam 28 are shelf-supporting brackets 29 that support shelf-forming plates 30 having angular stems 31, which, as shown, are mounted to slide into and out of angular seats formed in the respective hangers 29.

An apron wall 32 is built on the beam 28 and shelf-forming plates 30 and is thus supported independently of the arch. The 40 space between the lower course of the apron wall 32 and the uppermost block 23 of the curved or bull-nose-forming portion of the arch will be filled in by fire bricks 33. When 45 the fire bricks 33 are removed, the apron wall 32 will remain in position.

By again directing attention to Figs. 1, 2, 3 and 4, it will be noted that the block hangers 19 are very much more narrow than the arch-forming blocks, measured in a direction longitudinally of the supporting beams 15-16, and that they will pass freely through the clearance passages 27 of said blocks. Hence, it follows that when a block 50 hanger 19 is moved into alignment with the clearance passages 27 of a particular block, that block will drop or be forced downward out of its position in the arch, and it also follows that a new block may be replaced 55 by a reverse operation. When a block

hanger 19 is slid on the beam so as to position its outstanding ears 21 within the seats 25 and under the ledges 26, the block will, of course, be securely anchored to the beam. By the above arrangement of blocks and 70 block hangers, any particular block can be replaced without moving the block hanger out of the space normally occupied by the block, that is, without moving the said block hanger into an adjacent block. 75

In Figs. 7 and 9, a modified form of block hanger is illustrated and in this modified arrangement, the yoke-like portion 19^a of such block hanger, instead of having the outstanding ears 21, is provided with a centrally depending stem 19^b that terminates in a T-shaped head 19^c at its lower end. This head 19^c is adapted to be inserted into the block through the clearance passages 27 thereof and seated under the ledges 26 substantially by the same manipulations that are described in connection with the block hanger 19. Both forms of block hanger support the blocks directly under the supporting beams 15-16, and this, of course, gives 80 the best kind of protection to the beams. In Figs. 2 and 7, the numeral 34 indicates fire clay placed in the flaring joints between the upper portions of the arch-forming blocks. 85

Fig. 10 illustrates a modified form of block hanger having substantially the outline of the hanger shown in detail in Fig. 4, but in which the bar or body portion 19^a, which corresponds to the portion 19 of the hangers of Fig. 4, is made in two sections and the two sections are detachably connected by a removable pin 19^b. This hanger is provided with the inwardly projecting lugs, as in Fig. 4, and with the same kind of outstanding ears 21. The important advantage of this 90 sectional or two-part hanger is that a damaged hanger can be removed from the beam and a new hanger substituted therefor without disturbing the adjacent blocks or block hangers. Obviously, the block hanger is 95 made up of two hook-like sections, which, when connected, embrace the flange of the supporting beam and are slideable thereon and, when disconnected, may be readily detached from the beam flange. 100

What I claim is:

1. In a furnace arch, laterally spaced beams, block hangers each slideable on a single beam, and arch-forming blocks underlying said beams and detachably interlocked to said hangers, said blocks having vertical clearance passages adapting them to be detached from and interlocked with said hangers without sliding said hangers out of the space normally occupied by said blocks. 110

2. In a furnace arch, laterally spaced beams, block hangers each slideable on a single beam, and arch-forming blocks underlying said beams and detachably interlocked to said hangers, said blocks having vertical 115

- clearance passages adapting them to be detached from and interlocked with said hangers without sliding said hangers out of the space normally occupied by said blocks, said 5 arch-forming blocks being hung in a single layer underlying said beams and with their longitudinal joints spaced between beams.
3. In a furnace arch, laterally spaced beams, block hangers each slideable on a 10 single beam, and arch-forming blocks underlying said beams and detachably interlocked to said hangers, said blocks having vertical clearance passages adapting them to be detached from and interlocked with said hangers without sliding said hangers out of the 15 space normally occupied by said blocks, said beams having upwardly curved ends and the blocks applied thereto being wedge-shaped and affording a radial structure at the inner end of the arch.
4. The structure defined in claim 3 in which said beams are provided with detachable beam tips on which the upwardly curved ends thereof are formed.
5. The structure defined in claim 3 in further combination with an apron wall supported independently of said arch, and filler blocks interposed between said arch and the upper of said wedge-shaped blocks and extending from the outer substantially to the 20 inner portions thereof.
6. In a fire arch, laterally spaced beams, block hangers slideably on said beams, and arch-forming blocks underlying said beams and detachably interlocked to said hangers, 35 said block hangers being in the form of flat metal loops with inturned upper ends for engagement with the beam flanges and having outwardly projecting lips, said blocks in their tops having undercut ledges and 40 vertical clearance passages for co-operation with the outstanding lips of said block hangers, said undercut ledges serving to support the blocks on said lips and said clearance 45 passages permitting the blocks to be dropped from position.

In testimony whereof I affix my signature.
CLARENCE A. STRACHOTA.
